AUTOMATIC MACHINE

Ferdinand Lindgren, Cincinnati, Ohio

Application August 6, 1935, Serial No. 34,969

26 Claims. (Cl. 29—38)

This invention relates to automatic machinery, and particularly to multiple spindle machinery generally termed automatic drilling and tapping machines, but which are adapted to drill, counter-bore, tap, screw, counter-sink, ream, form, spot, spin, and perform divers other machining operations.

A number of multiple spindle machines have been proposed in the past, and a number of these have had a considerable commercial success, however, practically all of these were limited to operating upon only one or two sides of the work unless very costly work carriers were provided with complicated mechanisms adapted to turn the work on the work carrier between successive machining stations.

It is an object of the present invention to provide a compact yet highly efficient machine adapted to perform various machining operations on two or more than two sides of the work and even on directly opposite sides of the work without turning the work on the work carrier.

It is another object of the present invention to provide an automatic multiple spindle machine adapted to be quickly tooled for a small number of machining operations, and for a very large number of operations.

It is a further object of the present invention to provide an automatic multiple spindle machine which may be easily and quickly changed in setup for machining different pieces of work. In the past many machines of this type were single purpose machines which necessitated a complete factory rebuilding in order to change over from one type of work to another.

It is a still further object of the present invention to provide an automatic machine with a simple unitary driving mechanism equally applicable for indexing the work carrier and for driving one or all the machining tools.

It is another object to provide a machine adapted to support and drive one or more auxiliary machining tools.

In the accomplishment of these objects various novel features of construction were developed, and among these is the provision of: a novel work carrier; a distinctive mechanism for indexing and locking the work carrier; vertical and horizontal tool heads which are interchangeable and equally operative on two sides of a work carrier, and novel associated mechanism adapted to support and drive the tool spindles in said heads on either or both sides of the work carrier; a single drive shaft adapted to directly impart one, two, three, and four-way movement to a

plurality of horizontal and/or vertical tool spindles; and, a number of coadjutant and auxiliary tool spindles radially about the work carrier, and a simple cooperating driving mechanism.

Other features and advantages will appear hereinafter.

In the drawings:

Figure 1 is a small-scale general view of the entire machine provided by the present invention.

The machine of this invention, in its present preferred embodiment, comprises a base 30 having a substantially hollow, vertical chamber 31, integral transmission box 32, and a preferably integral table 33 rotatably supporting a work carrier 34 to move pieces of work 35 to various operative stations on the machine.

10

Work carrier

The work carrier 34 provided by the present invention is of novel construction and should be particularly noted, for the same work supporting table 36 may be arranged to rotate with the work 35 or to be stationary while the work is slid thereover, and with the latter arrangement is adapted to eject or clear the pieces therefrom.

The work carrier 34 comprises an annular index ring 37 provided with any desired number of index apertures 38 (18 in the present instance) rotatably supported in a channel 37' in the table 33 and having a standard 39 extending upwardly therefrom, either integral therewith or, as shown, made separate and secured thereto by screws 39', with a base section thereof overlying the apertures 38 and the inner edge of the channel 37' to prevent chip trouble. Externally of the index ring 37 there is provided a stationary ring 40 secured to the table 33 by screws 40' and preferably having its base extending over the annular index ring 37 to hold the latter in the channel 37' and to prevent chips from entering the channel. An annular work table 36 overlying the top of the stationary ring 40 and overlying a flange 41 on the standard 39 is provided with inner and outer sets of holes 42 and 43 respectively to accommodate one set of screws 44. An annular work locator plate 45 overlies the work supporting table 36 and is secured to the standard 39 with a set of screws 45' to be rotatable with the index ring 37 and standard 39, and is provided with a series of pockets 46 (36 in the present instance, double the number 45 of index apertures 38) to locate pieces of work 35 properly relative to the tool spindles while the standard 39 and work table 36 locate the work in proper position vertically.

When the set of screws 44 is passed through the inner set of holes 42 and secured to the flange 41 on the rotatable standard 39 the work table 36 is rotatable with the locator plate 45 and the work is manually loaded and unloaded.

If the same set of screws 44 is passed through the outer set of holes 43 and secured to the stationary ring 40, the work locator 45 alone rotates and slides the pieces of work 35 arcuately thereover. This latter construction is advantageous when it is desired to unload the work carrier 34 automatically. To this end the invention provides removable section 47 in the work table 36 just short of the loading station to permit the pieces of work 35 to drop downwardly out of the locator 45 into a chute 48, thence into a box or into a work conveyor. Thus, the operator need only load the work carrier and need not unload it.

If preferred, and as will be understood by persons in the art, the index ring 37, standard 39, work table 36, and locator plate 45 can be made integral and notched to receive only one type of work; or may be made integral, except for the locator plate 45 and work table 36 which may be made either separately or integral, and the latter

may also be made in the form of replaceable blocks to take different types of work.

Although it is possible to manually move the work carrier into desired operative position in relation to the various tool spindles, the present invention provides mechanism adapted to do this automatically and in timed relation with the operation of the various tool spindles and to lock it in the various stations.

Indexing and locking

Indexing and locking of the work carrier 34 in predetermined arcuate or machining stations is, in the present preferred form of the invention, accomplished by a feed arm 49 which is at its lower end pivotally mounted on a stud 50 to the base 30, and at its upper end provided with a finger 51 adapted to cooperate with successive index apertures 38 in the index ring 37 as shown in Figs. 7 and 12 when the feed arm is moved from the advanced to the retracted position, and to engage the aperture and index the ring one station to the position shown in Figs. 7 and 8 as the feed arm is moved into advanced position.

Movement of the feed arm 49 from retracted to advanced position is effected by a cam 52 on a slow speed shaft 53 engaging with a roller 54 on the arm 49 adapted to permit the arm to be pulled into the retracted position shown in Figs. 12 and 13 by a spring 54' connected to the arm 49 and to the base 30, as permitted by the low point of the cam and is urged from this retracted position into the advanced position shown in Figs. 7, 8, and 9 by the high point of the cam as the latter rotates. The finger 51 is secured to a stud 55 and the latter is capable of both pivotal and reciprocatory movement in bearings 55' on the arm 49. As viewed in Figs. 7, 10, and 12 it is normally moved in a clockwise direction by a flat spring 56 and is urged against the side wall 49' by another flat spring 57. These springs permit the finger 51 to be rotated in a counter-clockwise direction as the arm swings from the advanced to the retracted position as shown in Fig. 10 until the top end of the finger engages the next succeeding aperture, whereupon it snaps into the position shown in Figs. 12 and 13 while the spring 57 allows the stud 55 and finger to be reciprocated toward the other side wall 49' as the engaged aperture moves toward the center of the base in its relation with the pivot stud 50 of the arm 49 as will be apparent by viewing Fig. 13 first, then Fig. 8.

Holding and locking the work carrier 34 in advanced position is accomplished by two mechanisms. A stud 58 backed by a spring 59 and riding on the index ring 37, see Fig. 2, is adapted to frictionally hold the index ring in advanced position so that the finger 51 as it slides toward the retracted position, as shown in Fig. 10 will not retract the ring. Although it is possible to effect the arcuate step by step rotation of the work carrier by the arm 49 and finger 51 and hold it in advanced position by the frictional holding stud 58, as just described in detail, in its preferred form the present invention provides additional mechanism adapted to positively align and lock the carrier in its successive working stations. This latter mechanism comprises a latch 60 in the form of a plunger 61 in a sleeve 62 underlying the apertures 38 of the ring 37, adapted to be forced into these apertures by a spring 61'. The stud is through a rod 63 con-

75

nected to a forked plate 64 having a roller 64' at its lower end engaging with a cam 65 on the slow speed shaft 53. This cam is shaped and located on the shaft in particular relation with 5 the index cam 52 so that the high point thereof moves against the roller 64 and pulls the interconnected plunger 61 downwardly out of engagement with the associated aperture and out of the path of travel of the ring 37 when the feed arm 10 49 and associated finger 51 are moved toward or into the retracted position, and during initial movement of these toward the advanced position.

As the work carrier 34 approaches the next successive station, the low point of the cam 65 15 moves toward the bottom of the shaft, and permits the spring 61' to push the plunger into the aperture 38. Thus, the ring is positively located. Should the feed arm advance the ring slightly too much or too little, the plunger automatically takes care of this discrepancy.

It is within the purview of this invention to use notches and other like mediums cut into the index ring; however, in order to improve the 25 wearing qualities, and to make possible the replacement of the wear point, it is preferred to provide circular holes with bushings 38' set therein.

Because the feeding mechanism, and the locking mechanism for the work carrier are operated 30 by the one drive shaft on which the cams 52 and 65 are rigidly secured in fixed relation, and since both these mechanisms feed and lock through engagement with the same index apertures 38 on the work carrier 34, a novel, positive, 35 and a very effective indexing and locking is provided by the present invention.

Tool heads

It should be particularly noted that the present 40 invention provides, supports, and drives a large variety of tool spindles at various arcuate positions both interiorly, exteriorly and above the annular work carrier 34.

Horizontal tool heads 66 (see Figs. 2, 3, 4, 15, 16) are provided by the present invention which are equally adaptable for location and operation inside of the work carrier, for example tool heads A and B, or exteriorly thereof, for 20 example the tool heads C, D, E, and F, and are capable of imparting one, two, three, and four-way motion to the tools carried thereby, whether they be interiorly or exteriorly of the work carrier. Screws 67 engaging threaded holes 67' secure the tool heads to the table 33 and 33'.

In general the horizontal tool heads 66, best seen in Figs. 2 and 3, each comprises a housing 68 with suitable channels 69 and plates 69' adapted to receive a tongue 70 on tool slides 71 and to guide the latter in limited reciprocatory movement. As shown, each slide is provided with a pair of hollow tool spindles 72 adapted to receive the tapered shank of desired tools, for example, a tapered shank 73 of the drill chuck 73' as shown in Fig. 2. A flange 74 at one end of the spindle, and a long gear 75 at the other end, holds the spindle in the slide. If preferred, these spindles may be yieldingly mounted in any of the usual methods. A knock-out hole 72' facilitates removal of the tools carried by the spindle. The slide itself provides a satisfactory bearing for rotatably supporting the tool spindles. A large gear 76 meshing with the small gears 75 rotates the tool spindles. A tongue and slot connection 77 permits use of the same large gear 76

with pulleys 78 and 79 of the heads A and E, and with gears 80 and 81 of the heads B and F respectively as shown in Fig. 20.

Reciprocation of the tool slides 71 toward and from the work 35 transported by the carrier 34 is, as at present preferred, accomplished through the provision of a bell-crank 82, pivoted on a stud 83 extending between the side walls of the housing 68 and having a gear sector 84 meshing with a rack 85 on the underside of the slide 71 while an arm 86 is associated with various types of driving connections soon to be described. A coil spring 87 located and supported in a socket 87' section of the slide 71 and engaging a plate 88 secured to a front wall of the housing, normally urges the tool slide rearwardly in the housing to a back or inoperative position.

Vertical tool heads 89 capable of imparting two, three, and four-way movement to various tools carried thereby, are also provided by the present invention, and are equally locatable and operable interiorly and exteriorly of the work carrier; for example, a tool head G adapted to drill the pieces of work 35 and head H adapted to tap vertically. Screws 90 engaging threaded holes 90' secure the vertical heads to the table 33 and 33' interiorly or exteriorly of the work carrier 34.

These vertical tool heads 89 in their present preferred form each includes a main frame 91 having a set of pillars 92 adapted to receive and support a slide 93 for vertical movement. The slide carries a long gear 94 and through arms 95 adjustably supports a plurality of vertical tool spindles 96 having gears 96' at their upper ends 35 and supporting an intermediate gear 97 on fingers 97'. The tool spindles 96, gears 96' and 97 are brought into operative relation with the work and with the long driver gear 94 and are held there by lock screws 98.

One-way and two-way rotation of the tool spindles is accomplished by the drive shaft 99 and bevel gear 99' meshing with a cooperating bevel gear 100' at the lower end of a vertical shaft 100 and through a large gear 101 on this same shaft meshing with the long gear 94 just described. Reciprocation of the spindle carrying slide 93 is, as may be seen best in Fig. 18, accomplished through a cam 157 moving a connector rod 102 vertically in a bearing 103 by a finger 104 secured to the top end thereof while the latter raises a stud 105 and the associated slide or allows it to move downwardly. A thread and nut connection 106 provides a vertical adjustment for the slide 93.

Driving mechanism

The novel driving mechanism provided by the present invention, in its present preferred form, comprises only one high speed main drive shaft 108, hereinafter referred to as the rotatory drive shaft, and only one slow speed main drive shaft 53 hereinafter referred to as the reciprocatory drive shaft, adapted to impart one, two, three, and four-way movement to the individual tools, to index and lock the work carrier and to perform divers other operations in a manner about to be described in detail.

The rotatory drive shaft 108 is supported in the bearings 109, 110, and 111 in the web 112, and side walls 49' and 111 respectively of the base 30, and in the present form has a large gear 113 and small gear 114 secured at one end, and a small bevel gear 115 secured at the other end to limit endwise movement, and has a pair of pulleys 116

and 117 and a bevel gear 118 secured near the center thereof. An electric motor 119 suitably secured to the base, has a gear 120 meshing with the large gear 113 to impart high speed rotation to the rotatory shaft 108.

One-way movement, (e. g. rotation for drilling) may be imparted to tool spindles internally, externally, and vertically relative to the work carrier by the one rotatory drive shaft. The internal tool spindles 72 on the tool head A are given uni-directional movement through a belt connection 121 between the pulleys 78 and 117, the former being associated with and imparting rotation to the gears 75 and 76. By merely replacing the pulley 78 with the pulley 78' upon a slightly longer stud (see Fig. 20), the head A may replace the head G externally of the work carrier as is clearly shown in Fig. 16 wherein a pulley 117 is on the outer end of the shaft 108 and the belt 121 used exteriorly of the base.

The tool spindles 96 on the vertical spindle head G, as shown, are rotated by a belt connection 122 extending between the driving pulley 123 on the rotatory shaft to the driven pulley 124 on the tool head, the latter through the shafts and gears previously described imparting uni-directional rotation to the associated tool spindles.

Thus, it will be seen that the one rotatory drive shaft 108 is adapted to impart a high speed one-way movement to both the horizontal and the vertical tool spindles internally, externally, and vertically above, (viz, on three sides) of the work.

The main drive shaft 108 may also be used to drive a conventional hopper mechanism supported in any suitable manner above the center section of the table, for example through a suitable belt connection extending from the pulley 116 on the rotatory shaft upward through the central opening 125 to a pulley on any conventional hopper mechanism.

The reciprocatory drive shaft 53, so called because it is used mostly to translate rotation into reciprocatory movement, is also supported similarly to the rotatory shaft in bearings 126, 127, and 128, in the web 112, and side walls 49' and 57. This reciprocatory shaft supports a number of gears and cams which may be best described individually. At the left side, as viewed in Fig. 2, it is provided with a large gear 129 meshing with a small gear 114 on the rotatory shaft 108 in order to be driven by the latter at a considerably reduced ratio.

Two-way rotation of the spindles 72 and 96 in the horizontal and vertical tool heads 66 and 89 respectively, both internally and externally of the work carrier 34 is accomplished directly from the one reciprocatory drive shaft 53 with several novel forms of mechanism provided by the present invention. One form applied to a horizontal tool head 66, but equally applicable with the vertical head 89, is shown in Fig. 15. It comprises a rocker member 130 pivoted on a stud 131 with a pitman connection 132 on a rod 133 at its lower end including a bearing block 134 carried by a driver block 135 on the outer end of the reciprocatory shaft 53. A chain 136, meshing with a sprocket 137 on the tool head is secured to the rocker member 130 with a clamp plate 138 and spring connection 139. As the shaft 53 rotates the driver block moves from the solid line to the dot-and-dash line position shown in Fig. 15 to oscillate the rocker member and to rotate the sprocket 137, and the associated gear 78, gears 75

and spindles 72 in right hand and left hand direction of rotation. The chain provides a very silent drive.

A similar but more economical two-way drive mechanism is shown in Fig. 14, (applied in Figs. 2, 3, 17, 18, and 19) which includes the same pitman connection 132 but provides a modified rocker member 130' with an integral or attached gear segment 140 adapted to mesh with gears, for example gears 80, 81, and 141, to drive associated spindles 72 and 96.

The tool spindles 72 carried by the internally located tool head B are given two-way rotation through the provision of a driving connection 142 including a rack 143 meshing with a small gear 80 on the stud 80' while a block 144 also pivoted on the stud forms a reciprocatory bearing for the rack and maintains it in peripheral spaced relation to the gear thus permitting the entire rack to be oscillated slightly about the stud. At its lower end the rack is connected to a fork 145 having an elongated slot 146 riding vertically on the shaft 53 and having a roller 147 riding on a cam 148 carried by the reciprocatory shaft. As the high point of the cam is rotated toward the top of the machine it works against the roller and raises the rack vertically relative to the gear 80 and thereby imparts one-way rotation to the spindles 72 through the gear 76 and associated gears 75 and 80. And as the cam moves toward the bottom of the machine, a roller 149 affixed to the lower end of the fork is pushed downwardly and thereby causes the rack through the gears to move the associated tool spindles in the other direction. This entire type of two-way spindle driver may be used with equal facility on the exterior of the machine (for example, to drive the externally located horizontal tool head D or the vertical tool head H) and may be used on the vertical tool head when the latter is placed within the work carrier ring without change either to the two-way driver or to the tool head.

Two-way reciprocation of the horizontally disposed tool slides 71 and associated spindles 72 in the tool heads 66, for example the internally located tool head B, is accomplished by a connector 150 secured to the arm 86 on the bell crank 82 including a forked plate 151 embracing the reciprocatory shaft 53 and with a roller 152 resting upon a cam 153. A roller 154, or some equivalent means, may be used to pull the connector 150 down and associated slides 71 back. The cam 153 moves the forked plate 151 vertically up and down through a limited range of movement, and imparts arcuate movement to the bell crank and reciprocatory movement to the tool spindle slide. The same cam, forked plate, and connection 153, 151, and 150 may be located between the bearings 126 and 128 and may be used to drive a horizontal tool spindle head 66 exteriorly of the work carrier, for example if the tool head B was placed on the table in the location of the present vertical tool head G, the same connector 150 except for an offset forked arm 151' may be used for the head A.

Plain two-way reciprocatory movement for the horizontally disposed tool spindles 72 is sometimes desirable; for example, when it is desired to have fingers on the tool spindles 72 move in onto a piece of work transported by the work carrier 34 to perform some light forming operation or, for example, to overlie the piece of work 35 in the carrier 34 to prevent it from being pulled out by the tools carried by the vertical

tool head as the latter are pulled from the work, and for various other like reasons. In such uses it is merely necessary to place and tighten a set screw 155 to prevent the spindles from turning 5 and in such cases, of course, no rotatory driving connection is made.

Three-way movement of the horizontal spindles is accomplished by merely keeping the simple rotatory driving connection 121 or 122 or by keeping 10 a similar slow speed one-way rotatory driving connection with the shaft 53 in combination with the reciprocatory driving connections just described. Four-way movement to the horizontal tool spindles is accomplished through the provision 15 of the reciprocatory driving connections just described in combination with the two-way rotatory drive of the rack 143 type, of the gear segment 140 type, or of the chain 136 type hereinbefore described.

Similar one, two, three, and four-way movement of the vertical tool spindles 96 internally and externally of the work carrier 34 is accomplished by the provision of a very similar connector 102 extending from the finger 104 to a forked 20 plate 156 and to a cam 157 carried by the reciprocatory shaft and having a roller 158 engaging the cam 157. The vertical tool spindles may be locked against rotation by tightening set screws 159 thereagainst when it is desired to have 25 plain two-way reciprocatory movement, of the tool spindles. Three-way movement is accomplished by combining the one-way rotatory drive between pulleys 124 and 125 with the reciprocatory drive. Four-way movement is accomplished 30 by combining any of the two-way rotatory drives hereinbefore described in detail with the reciprocatory drive just described.

The motor 119 connected to any suitable source 40 of power with a switch in the usual manner is adapted to drive the rotatory shaft at a high speed through the gear 120 on the armature shaft engaging the gear 113 on the rotatory shaft and the latter through a small gear 114 and large gear 129 drives the reciprocatory shaft 53 at a slow 45 speed; thus there is a coordinate driving relation between the rotatory drive shaft 108 and the reciprocatory drive shaft 53 in which high speed rotation of the tool spindles and reciprocation of the spindles, and indexing and locking of the work carrier 34, is accomplished in timed relation. Also, by connecting the pulley 124 to the reciprocatory shaft rather than the rotatory shaft, and shortening the belt connection 122, the spindles 50 may be driven in one direction at a slow speed rotation.

The reciprocatory driving shaft 53 of the present invention thus provides a simple yet highly efficient single means adapted to impart slow speed rotation to the tool spindles; two-way rotation to the tool spindles; impart two-way plain reciprocatory movement to the tools; impart both reciprocatory and slow speed rotatory movement; and to impart reciprocatory and two-way rotatory movement, to horizontal tool spindles interiorly and exteriorly and vertical tool spindles vertically relative to the work carrier.

This same shaft, and a pulley 160 thereon, may be used to drive an oil pump 161 through a belt 161', as shown. Further, the same pulley, or a similar one, may be placed on the shaft between the bevel gear 162 and collar 163 in order to drive a belt through the opening 125 extending to a hopper feed or like mechanism supported on the center section of the table 33.

Coadjutant tools

The present invention provides a novel arrangement in which additional tools are provided in close relationship to the main drive shafts 53 and 108 and the tool head G. In the present preferred embodiment this novel arrangement comprises shaping the transmission box 32 so that the table extension 33' thereon extends arcuately on either or both sides of the main shafts to provide a support for either or both the horizontal and/or vertical tool heads 66 and 89. As shown in Fig. 3 particularly, the extension supports the two horizontal heads C and D for 15 drilling and tapping respectively, but the vertical head 89 arranged to drill or tap may be used with equal facility at either station.

To this end the transmission box is provided with a set of bosses 165 (see Fig. 6) supporting intermediate gears 166 on studs 167 and other bosses 168 and 169 supporting coadjutant rotatory drive shafts 170 and gears 193 thereon, with extensions 170' adapted to receive driving pulleys similar to the pulley 123.

Higher in the same transmission box between bosses 171 and 172 in the side wall 111 and cross web 112, the present invention provides a pair of coadjutant reciprocatory drive shafts 173 having beveled gears 174 on the inner ends thereof meshing with a main bevel gear 175 on the main reciprocatory drive shaft, to be rotated coordinately therewith, and having projections 173' extending on the outer ends thereof to receive driving pulleys or to receive the driver block 135 for the two-way rotatory drive. With this type of drive the shafts 173 rotate a different hand than the main drive shaft 53. If preferred the shaft may be built up like the coadjutant rotatory drive shafts 170 with intermediate gears to provide like direction of rotation between the main and coadjutant reciprocatory shafts 53 and 173.

The projections 170' on the coadjutant rotatory shafts 170 may be provided with a pulley 123 and thereby impart high speed rotation to the spindles 72 of the heads C and D or an equivalent head, and the projections 173' on the coadjutant reciprocatory shafts may be provided with pulleys or crank-arms to impart slow speed rotation or two-way rotation to the tool heads overlying these stations. The table 33' (see Fig. 3) underlying the heads C and D, for example, is provided with apertures similar to the openings 164 to clear the bearing 103 of the vertical tool head 89 and the connector 159 of the vertical tool heads 66 so that the reciprocatory drives already described in connection with the horizontal and vertical tool heads may be connected to the coadjutant shafts 173 between the bosses 171 and 172. Preferably the shafts are provided with the usual lift cam during the initial assembly of the machine so that it is merely necessary to drop the forked finger down onto the shaft, as will be readily appreciated by anyone familiar with machine construction.

Thus, the present invention provides a plurality of coadjutant supports and driving mechanisms to make possible a plurality of coadjutant tool heads in group association with the main driving mechanism.

Auxiliary tools

In addition to the coadjutant radiating tool stations the present invention provides other radiating tool stations adapted to perform subsequent and complementary machining operations

on the pieces of work transported by the work carrier 34. One of these auxiliary tools is best shown in Figs. 2, 3, 17, through 20, 23, and 24, and comprises what may best be termed single auxiliary transmission box 176 having a main frame 177 supporting an auxiliary rotatory shaft 178, auxiliary reciprocatory shaft 179 adapted through tongue and slot connections 180 and 181 to mesh with intermediate rotatory and reciprocatory shafts 182 and 183. Bolts 184 entering holes 184' in flanges 185 serve to connect the box 176 or the like to the main base 30 of the machine. The intermediate shafts 182 and 183 through bevel gears 186 and 187 thereon, and cooperating 15 bevel gears 188 and 189 on the main shafts 188 and 53 are adapted to impart rotation to the intermediate auxiliary shafts 182 and 183.

When this auxiliary transmission box is secured to the frame, either the horizontal or the 20 vertical tool heads 66 or 89 may be secured to the top thereof, shafts 178 and 179 associated with shafts 182 and 183 are capable of imparting one, two, three, and four-way movement to the spindles carried thereby in exactly the same manner as has already been described in connection with the main and coadjutant machining stations.

Interiorly of the box 176 the shaft 179 is provided with the previously described lift cam and 30 is provided with a cut out previously described, or 169, (Fig. 24) to make possible the reciprocatory drive to the tool head. A cover plate 177' on the bottom facilitates assembly within the box and keeps the oil and grease therein.

35 On the side of the machine opposite the main transmission box 32 there is shown a triple station auxiliary transmission box 188 including a frame 189 adapted to be secured to the flanges 185 with screws 184. In general it embraces the 40 principles of the main transmission box 32 and the auxiliary transmission box 176 last described, differing only in the provision of a removable three station table 190 thereon adapted to receive three tool heads 66 and/or 89 and in the provision of a self-contained driving mechanism for the three tool heads. This triple auxiliary transmission box may best be seen in Figs. 1 through 6, 21 and 22. This box is provided with central bearings 191 and 192 adapted to receive 50 the auxiliary rotatory and reciprocatory shafts 178 and 179, like those in the single auxiliary unit 176 with the same tongue and slot connections 180 and 181 adapted to engage with and be driven by the main rotatory and reciprocatory 55 drive shafts 108 and 53. Further, the box is provided with holes 181' to receive the crank stud 181 of any of the three forms of two-way driving mechanisms hereinbefore described, and provided with a top center opening 164 adapted to clear 60 the bearing 103 or the connector 150 of the reciprocatory drive mechanisms for the tool slides. The pulley 123 on the end of the intermediate rotatory shaft 178 may be used to impart unidirectional high speed rotation to the tool spindles if preferred.

The auxiliary transmission box 188 (Figs. 21 and 22 particularly) also provides secondary bearings 171' and 172' adapted to support auxiliary coadjutant reciprocatory shafts 173' and 70 gears 174' and 175' similar to the shafts 173 and gear 174 and 175 best seen in Fig. 5, but in this instance having the gears slightly larger in diameter and mounted within the auxiliary box in a manner apparent to anyone skilled in this art. On a 75 lower plane the box is provided with auxiliary

bearings 168' and 169' and also bosses 165' adapted to receive and support an exact duplicate of the coadjutant rotatory gears 193 and shafts 170 and intermediate gears 166 respectively, best seen in Fig. 6. It includes secondary holes 164 in the top table section thereof to provide clearance for the bearing 103 and connector 150 of the tool slide reciprocating mechanisms. The shafts 179 and 173' may be provided with the lift cams and associated mechanism as already described. The various parts are preferably assembled within the box through an opening 195 in the bottom thereof. Afterwards the box is sealed with a plate 196 which, in effect, transforms the box into a grease or oil tight compartment in which the various parts may run.

This same triple auxiliary unit may be secured to the flanges 185 opposite the loading station as shown by the dot and dash lines 197 in place of the single unit. It will be apparent to anyone skilled in the art that a double unit, rather than the single or triple auxiliary unit may be made. It is also within the purview of this invention to have the transmission boxes 176 and 188 or two of the boxes made integral with the base 30 so that the machine is also provided with a large number of radiating tool stations exteriorly of the work carrier.

However, the auxiliary units and the method 20 of interchangeability provided by the structure of the present invention represents a much more advantageous structure since it is possible to considerably clear the spaces around the machine and to cut down the working load on the motor. In addition to the foregoing it is also possible to add special machining tools radically different from the tool heads hereinbefore described onto the machine and still have good support and a driving mechanism therefor.

Adjustment of the reciprocatory drive of the 40 various vertical and horizontal tool heads 66 and 89 is accomplished by thread and lock nut connections 198 on each. A door 199 on the side of the base 30 facilitates adjustment, repair, and assembly of parts within the base.

Operation

The motor 119 is started whereupon the shafts 108 and 53 are driven and the latter through the cams 52 and 65 oscillates the index arm 49 and reciprocates the plunger 61 to effect a step by step arcuate movement of the work carrier 34 to the various machining stations. The operator loads pieces of work into the carrier to the right of the chute 48. As the pieces of work are indexed to the station adjacent the head C, the drills 200 carried thereby, rotated and reciprocated by the mechanism hereinbefore described, are moved in to drill holes 201 in the pieces of work; in the next station the drills 203 carried by the head A are rotated and reciprocated to drill holes 204 in the pieces of work.

In the next station the taps 205 are reciprocated and given two-way rotation to rough tap the external holes 201. In this and in the preceding station the vertical spindles 96 are rotated and reciprocated to move drills 206 down into the pieces of work and form vertical holes 207 in the work. When the pieces of work are adjacent the tool head H, the taps 208 are reciprocated and rotated to tap the vertical holes 207, and when adjacent the head E the drills 209 are moved in to counter-sink the holes 201. When the work is adjacent the head F the taps 210

are given movement to finish tap the holes 201. In this same station the taps 211 are given movement to thread the holes 204 internally relative to the work carrier. As the work carrier moves 5 the work above the chute 48 the pieces drop by gravity downward into chute 48 if the work table 36 is secured to the stationary ring 40 and the section 47 is removed therefrom. When the section 47 is not removed, and when the table 36 10 rotates with the locator plate 45, the pieces of work are removed manually.

During these machining operations the main rotatory and reciprocatory drive shafts index and lock the work carrier in a step by step manner 15 and also impart the rotatory and reciprocatory movements to the horizontal and vertical tool spindles 12 and 96 carried by the tool heads A, B, and G in exact timed relation relative to each other. At the same time the main drive shafts 20 53 and 108 through the coadjutant drive shafts 173 and 170 impart three-way and four-way movement to the tool spindles 72 in the tool heads C and D in exact timed relation with the movement of the work carrier and the tool heads A, 25 B, and G.

Because the tool heads H, E, and F supported by the auxiliary transmission boxes 176 and 188 have a mechanical connection with the main drive shafts 108 and 53 through the tongue and 30 slot connections 180 and 181, these heads are also driven in exact timed relation with the work carrier 34 and the tool heads A, B, C, D, and G. It will be appreciated readily that with the structures of this invention various other combinations 35 of tools or machining operations may be made.

It is within the purview of this invention to make the various types and the variously conditioned and located tool heads, and also the coadjutant and auxiliary supports and driving 40 mechanisms, hereinbefore described in detail, integral with or substantially integral with the main base 30 although this represents a much less advantageous machine because it would in effect make but a single purpose machine and 45 one of the greatest and most important advantages of the preferred and shown embodiment is that it is widely interchangeable and that the machine itself can be greatly reduced in size in certain set-ups to facilitate working around it.

50 Also it will be understood readily that the tool heads 66 and 89 may be reciprocated by expedients other than the cams shown, and may each be provided with but a single tool spindle 72 and 55 96 respectively or only one of each of the two spindles in the individual tool heads provided with tools in which event the number of work carrying pockets 46 will equal the index apertures 38. Thus, the machine in general as hereinbefore described may be used to fabricate large 60 or very wide pieces of work.

Other variations and modifications may be made within the scope of the present invention, and portions of the improvements may be used without others.

65 I claim:

1. In a device of the character described, the combination with a base, of an annular work carrier; tool spindles interiorly, and exteriorly of said annular work carrier; at least one high 70 speed drive shaft extending radially from the vertical center of the base and work carrier; at least one slow speed drive shaft extending radially from the vertical center of the base and work carrier; and means associated with said high and 75 low speed drive shafts adapted to impart one and

two way rotation and to impart reciprocatory movement to said tool spindles.

2. In a device of the character described, the combination with a base, of an annular work carrier; tool spindles interiorly, exteriorly, and above said annular work carrier; at least one high speed drive shaft extending radially from the vertical center of the base and work carrier; at least one slow speed drive shaft extending radially from the vertical center of the base and work carrier; and means associated with said high and low speed drive shafts adapted to impart reciprocatory movement and also one and two-way rotation to said tool spindles interiorly, exteriorly and above said annular work carrier. 15

3. In a device of the character described, the combination with a base, of an annular work carrier; tool spindles interiorly, and exteriorly of said annular work carrier; spindle driving connections and only two main drive shafts adapted 20 to impart one and two way rotation and to impart reciprocatory movement to said tool spindles.

4. In a device of the character described, the combination with a base, of an annular work carrier; tool spindles interiorly, exteriorly, and above said annular work carrier; spindle driving connections and only two main drive shafts associated with said driving connections adapted to impart reciprocatory movement and also one and two way rotation to said tool spindles interiorly, 25 exteriorly and above said annular work carrier.

5. In a device of the character described, the combination with a base, of an annular work carrier; three motion tool spindles supported by said base interiorly and exteriorly of said work carrier; at least one high speed drive shaft extending radially from the vertical center of the base and work carrier; at least one slow speed drive shaft extending radially from the vertical center of the base and work carrier; and means 30 associated with said high and low speed drive shafts adapted to impart three motion operation to said interior and exterior tool spindles. 35

6. In a device of the character described, the combination with a base, of an annular work carrier; four motion tool spindles supported by said base interiorly and exteriorly of said work carrier; at least one high speed drive shaft extending radially from the vertical center of the base and work carrier; at least one slow speed 40 drive shaft extending radially from the vertical center of the base and work carrier; and means associated with said high and low speed drive shafts adapted to impart four motion operation to said interior and exterior tool spindles. 45

7. In a device of the character described, the combination with a base; of a rotatable work carrier; radially arranged tool spindles; a high speed main drive shaft; auxiliary drive shafts associated with said main drive shaft and radiating therefrom; and driving connections between said radial tool spindles and said radiating auxiliary shafts. 60

8. In a device of the character described, the combination with a base; of a rotatable work carrier; radially arranged tool spindles; a high speed main drive shaft; a slow speed main drive shaft; auxiliary drive shafts associated with said high and slow speed main drive shafts and radiating therefrom; and driving connections between said tool spindles and said radiating auxiliary shafts adapted to impart rotatory and reciprocatory movement to said tool spindles. 65

9. In a machine of the character described, the combination with a base; of a rotatable work 70 carrier; 75

carrier; a tool spindle; indexing mechanism; a pair of main drive shafts; and means on said pair of drive shafts adapted to coordinately operate the indexing mechanism and to impart 5 three-way movement to the tool spindle.

10. In a machine of the character described, the combination with a base; of a rotatable work carrier; a tool spindle; indexing mechanism; a pair of drive shafts; and means on said pair of 10 drive shafts adapted to coordinately operate the indexing mechanism and to impart four-way movement to the tool spindle.

11. A machine of the character described; having in combination with a base; an annular 15 work carrier; indexing mechanism; internal and external radial tool spindles; a pair of main drive shafts; and means on said pair of drive shafts adapted to operate the indexing mechanism and to impart three and/or four-way motion 20 to the tool spindles.

12. In a machine of the character described, the combination with a base having a plurality of arcuately arranged work stations; of a rotatable work carrier; tool spindles; means for 25 indexing the work carrier; a single driving means adapted to concurrently operate the tool spindles and the indexing means; and heads adapted to support the tool spindles for rotatory and reciprocatory movement, said heads being adapted to 30 be mounted at various arcuate work stations adjacent the rotatable work carrier, and in operative relation to the driving means.

13. In a machine of the character described, the combination with a base having a plurality 35 of arcuately arranged work stations, of an annular work carrier, rotatably supported upon the base; tool spindles; driving means; heads adapted to support the tool spindles for rotatory and reciprocatory movement, said heads being adapted 40 to be mounted at various arcuate work stations exteriorly and/or interiorly about the annular work carrier and in operative relation to the driving means.

14. In a machine of the character described, 45 the combination of a base having a table-like top; an annular work carrier rotatably supported upon the base; and tool spindle heads adapted to support the tool spindles for rotatory and reciprocatory movement, said heads being adapted 50 to be mounted upon a table-like top exteriorly and/or interiorly of the annular work carrier and at various arcuate work stations about the rotatable work carrier.

15. In a device of the character described, the 55 combination with a base, of a plurality of tool spindles; a rotatable indexing ring; a standard on said indexing ring, a stationary ring; a work table secured to said stationary ring; and a work locator on said standard, overlying said table, 60 and rotatable with the support on the indexing ring, and capable of sliding work located thereby over said table.

16. In a device of the character described, the 65 combination with a base, of a rotatable indexing ring; a standard on said indexing ring; a stationary ring; a table on said stationary ring, having a gap therein; a work locator on the standard, and rotatable therewith; and a chute underlying said gap, allowing work to drop from 70 the locator and table as the locator moves the work across the table into a position over the gap.

17. In a device of the character described, the 75 combination with a base, of a rotatable indexing ring; a standard on said indexing ring and rotat-

able therewith; a stationary ring; a work locator on said standard and rotatable therewith; and a work table underlying said locator capable of securing to the stationary ring so that work is moved over the top thereof during rotation of 5 the locator and capable of securing to said standard for rotation with the latter, and with the locator.

18. In a machine of the character described, the combination with a base, of a rotatable work 10 carrier, having a plurality of apertures therein; an arcuately movable arm pivotally connected to a support; means adapted to arcuately move the arm; and an arcuately movable finger on said arm, adapted to engage in successive apertures 15 of the work carrier and rotate the latter when the arm is arcuately moved in one direction and adapted to move clear of the engaged aperture and across the under side of the work carrier into a next succeeding aperture when the arm is 20 moved in the other direction.

19. In a machine of the character described, the combination with a base, of a rotatable work carrier, having a plurality of apertures therein; a movable member; mechanism for automatically 25 moving said member; and a finger on said member adapted to engage successive apertures in the work carrier and to arcuately move the carrier when the member is moved in one direction and adapted to move clear of the engaged aperture 30 and into a succeeding aperture when the member is moved in the other direction.

20. In a machine of the character described, the combination with a base, of a rotatable work carrier, having a plurality of apertures therein; 35 a movable member; mechanism for automatically moving said member; a finger on said member adapted to engage successive apertures in the work carrier and to arcuately move the carrier when the member is moved in one direction and adapted to move clear of the engaged aperture 40 and into a succeeding aperture when the member is moved in the other direction; and means adapted to support said finger for arcuatory and reciprocatory movement in the movable arm. 45

21. In a machine of the character described, having in combination with a base, of a rotatable work carrier; tool spindles; a feed dog adapted to arcuately advance the work carrier; a latch adapted to lock the work carrier in successive 50 arcuate stations; means adapted to reciprocate the tool spindles; and a main drive shaft adapted to operate the feed dog, latch, and the tool spindle reciprocating means in timed relation.

22. In a machine of the character described, 55 the combination with a disposed base; of a rotatable work carrier; internal radial tool spindles; external radial tool spindles; vertical tool spindles; a feed dog adapted to arcuately advance the work carrier; a latch adapted to lock the work 60 carrier in successive radial stations; means adapted to reciprocate the internal, external, and vertical tool spindles; and a main drive shaft adapted to operate the feed dog, latch and the tool spindle reciprocating means in timed relation. 65

23. In a machine of the character described, the combination of a base; a rotatable work carrier having apertures therein; a feed dog engaging said apertures adapted to arcuately advance the work carrier; a plunger underlying the work 70 carrier and engaging said apertures; and a main drive shaft adapted to operate the feed dog and plunger in timed relation.

24. In a machine of the character described, the combination of a base; a horizontally dis- 75

posed drive shaft; a cam on said drive shaft; a tool head on said base; a tool spindle; a tool spindle slide on said head; bell crank associated with the tool spindle slide; and a connector extending 5 from the bell crank to the cam on the horizontally disposed drive shaft adapted to reciprocate the tool spindle slide.

25. In a machine of the character described, the combination of a base; tool spindles; a main 10 support; a main drive mechanism providing a direct drive to tool heads on the main support; a coadjutant main support; and a coadjutant driv-

ing mechanism, associated with the main drive mechanism, adapted to drive the tool spindles on the coadjutant main support.

26. In a machine of the character described, the combination of a base; tool spindles; a main 5 support; a main drive mechanism; an auxiliary support; and an auxiliary driving mechanism in the auxiliary support, associated with said main driving mechanism, adapted to drive tool spindles on said auxiliary support. 10

FERDINAND LINDGREN.
